UNITED STATES PATENT OFFICE

166,136

SHOE

Seymour Troy, New York, N. Y.

Application October 22, 1951, Serial No. 17,060

Term of patent 3½ years

(Cl. D7—7)

To all whom it may concern:

Be it known that I, Seymour Troy, a citizen of the United States, residing at New York city, in the county and State of New York, have invented a new, original, and ornamental Design for a Shoe, of which the following is a specification, reference being had to the accompanying drawing, forming a part thereof.

The figure is a perspective view of a shoe, showing my new design.

The dominant feature of the design resides in the portions shown in full lines.

I claim:

The ornamental design for a shoe, substantially as shown and described.

SEYMOUR TROY.
